UNITED STATES PATENT OFFICE.

CHARLES E. GODLEY, OF DETROIT, MICHIGAN, ASSIGNOR TO EDMUNDS AND JONES MANUFACTURING COMPANY, OF DETROIT, MICHIGAN, A CORPORATION OF MICHIGAN.

LAMP.

1,093,122.

Specification of Letters Patent. Patented Apr. 14, 1914.

Application filed September 24, 1913. Serial No. 791,500.

To all whom it may concern:

Be it known that I, CHARLES E. GODLEY, a citizen of the United States, and a resident of Detroit, in the county of Wayne and State of Michigan, have invented a new and Improved Lamp, of which the following is a specification.

This invention relates to headlight and searchlight lamps, and its object is to provide means for holding the reflector and lens ring in position so that the lamp shall be dust-proof, and which shall prevent the rattling that commonly occurs when such lamps are used on vehicles, launches and the like.

A further object of this invention is to provide a locking means whereby the lens ring shall be positively locked in position, and yet may be easily and quickly detached when desired.

This invention consists in improved positioning and retaining means for the reflector of a lamp; also in improved means for retaining and locking the lens ring in position; and in such other details as are illustrated in the drawings and pointed out in the claims.

In the accompanying drawings, Figure 1 is a side elevation of the lamp. Fig. 2 is a longitudinal section thereof. Fig. 3 is a perspective view of the lamp-body. Fig. 4 is a perspective view of the reflector. Fig. 5 is a perspective view of the lens ring, showing a part of the locking means. Fig. 6 is a detail of the means for holding the lens ring in position. Fig. 7 is a detail of the spring for holding the reflector away from the lamp-body.

Similar reference characters refer to like parts throughout the several views.

In the drawings, 1 indicates a lamp-body, preferably of sheet brass, having a flared front end 2, a bead 3, and a cylinder 4 projecting from the bead 3. The flared front 2 and flange 3 together form a groove 5 within which a circumferential spring 6 is seated. This cylinder 4 is provided with a series of pins or projections 7 that ex-

tend from both the inner and outer sides of the cylinder 4, as indicated in Fig. 3.

The circumferential spring 6 is preferably made of a single piece of wire which is, in general, bent into a substantially circular form. At various points are formed the V-shaped loops 8, extending upwardly in an inclined direction from the plane of the body of the spring, as shown in Figs. 1 and 3. The ends of the wire are joined in the manner indicated in Fig. 7. One end is shaped somewhat like the letter S, and the other end is bent laterally at 9 and then passes over the extremity of the other end, then downwardly through the first bend of the S-shaped end and upwardly through the second bend of the S. The spring 6, after the ends are united, is forced into the cylinder 4, and is seated in groove 5, which it fits snugly as shown in Fig. 2.

The reflector 10 is preferably parabolic in cross-section, and its front portion terminates in a cylinder 11, which is bent back upon itself at 12 and then bent laterally to form a radial annular flange 13, having a series of notches 14, corresponding in number to the pins 7. By inserting the reflector into the cylinder 11 against the spring 6 in such manner that the notches 14 will register with the inwardly extending ends of the pins 7, and then turning it about its own axis, it is evident that the reflector will be retained in position in the lamp-body.

The lens ring 20 is shown substantially semi-circular in cross-section, one edge 21 being fitted resiliently over the bead 3 and the other edge 22 being adapted to fit resiliently against lens 23. The lens is held in position in the ring 20 by a series of retainers 24 that are fastened to the ring 20 at 25 by brazing or otherwise, as indicated in Figs. 2 and 5. These retainers project from the inner face of the ring and have bent arms 26 that extend along the edge of the lens. The arms 26 are provided with lugs 27 bent into a plane parallel to the plane of the lens, whereby the lens is held in place. When the lens is to be placed in

the ring 20, the arms 26 of the retainers are sprung outwardly far enough to allow the lens to pass between them, after which the lens is placed in position, and the retainers are allowed to spring back, or are bent back, into position.

Connected to the retainer 24, and preferably integral therewith, is a locking member 30, which is secured in any desired manner, preferably by brazing, to the inner face of the lens ring 20 at 25 and 31. This locking member is bent at 32 and stands out a short distance from the inner face of the ring 20. It is provided with an inclined edge or face 33 that terminates in a hump 34 beyond which is a depression 35 (see Figs. 5 and 6).

Assuming that the reflector has already been positioned within the body in the manner previously indicated and that it is desired to attach the lens ring 20 and lens 23 to the lamp-body, it will only be necessary to center the ring on cylinder 4 and then turn the ring about the axis of the lamp. In this movement the portions of pins 7 that project from the exterior surface of cylinder 4 will come into engagement with inclined edges 33 of locking members 30, and ride upon them, so that the lens ring will be drawn inwardly, pressing the lens against the outer edge of the cylinder 12 and depressing the spring loops 8. When the pins 7 pass these humps, they will enter the depressions 35, where they will prevent any rotation of the ring with respect to the body. The spring loops 8 will force the outer edge of the cylindrical flange 12 against the lens and through the lens and ring 20, hold the pins 7 in the depressions in the fastening members 30.

When it is desired to remove the ring 20 from the lamp-body it is only necessary to press inwardly upon it to overcome the force of spring loops 8, sufficiently to carry the humps 34 back of the pins 7, and then rotate it in the proper direction about the cylinder 4, until humps 34 shall have passed beneath pins 7, after which spring 6 will force the ring outwardly in respect to the body.

Any desired type of burner may be employed so long as the point of intense light can coincide with the focal center of the reflector. In Fig. 2 of the drawings a sleeve 38 is connected to the back of the reflector and carries a socket 39 that supports the bulb 40. A wire 41 extends up through the supporting tube 42 and connects to the inner end of the socket 39. The socket, reflector, lamp-body and support form the connection for the opposite end of the lamp filament.

It is obvious that many changes may be made in the details of my invention without

losing any of the advantages resulting therefrom. Thus locking members 30 might be secured to the lamp-body, pins 7 then being mounted on face ring 20.

Having now described my construction, what I regard as my invention and desire to secure by Letters Patent of the United States is:

1. In a lamp, a cup-shaped body having its edge integral therewith and extended in the form of a bead said edge and bead together constituting a groove within which a spring for supporting a reflector is seated.

2. In a lamp, a body having a flaring front end extended in the form of a bead and terminating in a cylinder, a series of pins projecting from the inner surface of the cylinder, said flaring front end and bead together constituting a groove within which a spring is seated, a reflector mounted within the cylinder and resting upon the spring, and means on the reflector for engaging with the pins to secure the reflector in position.

3. In a lamp, a lamp body, a reflector therein, a circumferential spring seated in the body and against which the reflector rests, said spring tending to force the reflector away from the body, means for retaining the reflector in the body against the force of the spring, a lens-ring secured to the lamp body, and means for retaining the lens ring in position on the body against the force of the spring.

4. In a lamp, a lamp body, a reflector therein, a circumferential spring seated in the body and against which the reflector rests, a lens ring mounted on the body and resting against the reflector, and means for locking the lens ring in position on the body against the force of the spring.

5. In a lamp, a lamp body, a reflector therein, a circumferential spring seated in the body and against which the reflector rests, said spring tending to force the reflector away from the body, a lens ring mounted on the body and resting against the reflector, pins projecting laterally from the lamp body, and locking means on the lens ring adapted to engage with the pins to hold the lens ring in position on the body against the force of the spring.

6. In a lamp, a lamp body, a reflector therein, a circumferential spring seated in the body and against which the reflector rests, said spring tending to force the reflector away from the body, a lens ring mounted on the body and resting against the reflector, pins projecting laterally from the lamp body, locking means on the lens ring adapted to engage with the pins to hold the lens ring in position on the body against the force of the spring, said locking means comprising an inclined face terminating in a ledge, and a depression beyond the ledge.

7. In a lamp, a lamp body, a reflector therein, a spring seated in the body and against which the reflector rests, a lens ring mounted on the body and resting against the reflector, and means for locking the lens ring and the body together against the force of the spring, said means comprising laterally projecting pins on one of the members to-be locked, and means on the other member 10 to be locked for engaging with the pins.
8. In a lamp, a lamp body, a reflector therein, a circumferential spring seated in the body and against which the reflector rests, a lens ring mounted on the body and resting against the reflector, and means for locking the lens ring and the body together against the force of the spring, said means comprising a lateral projection on one of the members to be locked together, and means 15 on the other member adapted to be engaged with the projection by an angular rotation of the second member in respect to the first.
9. In a lamp, a lamp body, a reflector and a lens ring mounted on the body, a circumferential spring seated in the body, said spring tending to separate the reflector and the lens ring from the body, and means to secure the lens ring and the body together, said means comprising a lateral projection 20 on one of the members to be secured, and a locking piece on the other member adapted to be engaged with the projection by an angular rotation of one of the members to be secured in respect to the other member, 25 said locking piece comprising an inclined face or edge terminating in a hump, and a depression beyond the hump.
10. In a lamp, a lamp body having a flaring front and a reversely bent portion that 30 together form a seat for a spring, a spring in the seat, said spring being substantially circular in shape, and comprising a series of V-shaped bends projecting at an angle to the plane of the base of the spring, a reflector resting against the spring, a lens ring secured to the lamp body, and means for retaining the lens ring in position on the body against the force of the spring.
11. In a lamp, a lamp body having a flaring front and a reversely bent portion that 35 together form a seat for a spring, a spring in the seat, said spring being substantially circular in shape, and formed of a single piece of wire having its ends bent together, and having a series of loops projecting therefrom at an angle to the plane of the base of the spring, a reflector resting against the spring, a lens ring secured to the lamp body, and means for retaining the lens ring on the lamp body against the force of the spring.
12. In a lamp, a lamp body having a flaring front and a reversely bent portion that 40 together form a seat for a spring, and terminating in a cylinder, projections on the inner and outer surfaces of the cylinder, a spring in the seat, a reflector having notches adapted to register with the projections on the inner surface of the cylinder, said reflector resting against the spring, a lens ring of sheet metal curved in cross-section, and a locking member secured to the ring and adapted to be engaged with the projections on the exterior of the cylinder by an angular movement of the ring about the cylinder, said locking member comprising an inclined face terminating in a hump and a depression beyond the hump.
13. In a lamp, a lamp body having a flaring front and extended in the form of a reverse bend, said flaring front and reverse bend together forming a rib on the outer surface of the lamp body and a groove on the inner surface of the lamp body, a spring seated in the groove, a reflector resting against the spring, a lens ring resting against the reflector, said lens ring being curved in cross-section and having one edge contacting with the rib, said spring tending to force the reflector and lens ring outward away from the lamp, and means on the lamp body co-operating with means on the lens ring for locking the lens ring on the lamp body against the force of the spring.
14. In a lamp, a lamp body, a reflector 95 therein, a resilient member seated in the body and against which the reflector rests, a lens ring mounted on the body and resting against the reflector, and means for locking the lens ring in position on the body against the force of the resilient member.
15. In a lamp, a lamp body, a reflector therein, a resilient member seated in the body and against which the reflector rests, a lens ring mounted on the body and resting 100 against the reflector, and means for locking the lens ring and the body together against the force of the spring, said means comprising a lateral projection on one of the members to be locked together, and means on the other member adapted to be engaged with the projection by an angular rotation of the second member in respect to the first.
16. In a lamp, a lamp body, a reflector mounted therein and provided with a radial flange engaging the lamp body, a lens ring fitting 115 said lamp body and revoluble thereon, and engaging devices between the lens ring and body.
17. In a lamp, a lamp body, a reflector mounted therein and having a radial flange engaging the lamp body, a lens ring fitting 120 said lamp body, and engaging members for holding the lens ring in position on said body and acting to lock or unlock the lens ring upon a limited revoluble movement of the lens ring on said body.
18. In a lamp, a lamp body, a reflector

therein, a lens ring fitting said lamp body, a resilient member positioned in the lamp body and exerting pressure on the lens ring when positioned on the body, and engaging 5 members for holding the lens ring in position on said body and acting to lock or unlock the lens ring upon a limited angular movement of the lens ring on said body.

In testimony whereof I have signed this specification in the presence of two subscr- 10
ing witnesses:

CHARLES E. GODLEY.
